UNITED STATES PATENT OFFICE

JOHN LEO DOWD, OF MERIDEN, CONNECTICUT, ASSIGNOR TO INTERNATIONAL SILVER COMPANY, OF MERIDEN, CONNECTICUT, A CORPORATION OF NEW JERSEY

DESIGN FOR A CHILD'S PLATE OR OTHER SIMILAR ARTICLE

Application filed August 10, 1932. Serial No. 44,574. Term of patent 7 years.

To all whom it may concern:

Be it known that I, JOHN LEO DOWD, a citizen of the United States residing at Meriden, county of New Haven and State of Connecticut, have invented a new, original, and ornamental Design for a Child's Plate or Other Similar Article, of which the following is a specification, reference being had to the accompanying drawing, forming a part thereof:

Fig. 1 is a top plan view of a plate showing my new design;

Fig. 2 is a side view of the plate partly in vertical section on the line A of Fig. 1; and

Fig. 3 is a side view of the plate partly in vertical section on the line B of Fig. 1.

I claim:

The ornamental design for a child's plate or other similar article, substantially as shown.

JOHN LEO DOWD.
